INVENTOR

David Felgar,
by E. W. Anderson
his ATTORNEY

UNITED STATES PATENT OFFICE.

DAVID FELGAR, OF STUART, IOWA.

AGRICULTURAL BOILER.

SPECIFICATION forming part of Letters Patent No. 225,814, dated March 23, 1880.

Application filed November 29, 1879.

To all whom it may concern:

Be it known that I, DAVID FELGAR, of Stuart, in the county of Guthrie and State of Iowa, have invented a new and valuable Improvement in Agricultural Boilers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a horizontal section of my improved generator; and Fig. 2 is a front view thereof, with the steaming-vessel in section.

This invention has relation to improvements in agricultural boilers for domestic, farm, and other purposes.

The nature of the invention consists in the construction and novel arrangement of parts, as hereinafter shown, described, and set forth in the claim.

In the accompanying drawings, A designates a rectangular vessel, usually made of sheet-iron, and steam-tight at all its joints. B indicates the fire-box, arranged at one end of the vessel or shell, and opening through the front of the same, as shown in Fig. 2.

The fire-box B is surrounded at its sides, top and bottom, and end by the water-space of the generator, and it is provided with a grate, C, an ash-pit under it, and a hinged door, D, closing its front end.

E indicates a smoke-pipe, extending from the side of the fire-box, near its rear end, and being bent into the form of an open rectangle, as shown in Fig. 2, passing through the side of the vessel A. At no point does this pipe, except as above mentioned, come in contact with the sides, end, or bottom of the said vessel, being completely insulated, as it were. This arrangement of the fire-box and smoke-pipe secures the largest possible extent of heating-space consistent with an economical construction of this description of generator, and the heat radiated from every part of the box and pipe is utilized to heat the water, cause it to speedily boil, and give off steam.

The front of the boiler is provided with the usual gage-cocks *a*, and its upper part with a safety-valve, *b*, opening into its steam-space. Water is supplied to the boiler through a feed-pipe, G, having a cut-off cock, *c*, and the steam, as it is generated, is conducted into a vessel, G', containing feed or other material to be cooked, through a pipe, L, which is likewise provided with a cut-off cock, *d*. These pipes may be either rigid or flexible. The vessel G' is provided inside with a permanent steam-pipe reaching down its side, and, having reached its bottom, carried toward its central part. Pipe *p* extends through the side of vessel G', and terminates in a nozzle, *n*, by means of which it is coupled to the steam-pipe L. At its upper edge the vessel G' has a ledge, *i*, and the lid N the usual projecting bearing-flange *i'* and holding-flange *i''*. Upon the latter is applied a rubber packing-ring, *i³*, which, when the lid is in place, is compressed between the ledge *i* and flange *i'*. The lid is held in place by means of a bridge, O, having at each end a vibrating bail, *l*, that engages a strong lug or ear, *o*, on the upper part of the vessel, and a set-screw, S, passing through the bridge and bearing against the lid.

What I claim as new, and desire to secure by Letters Patent, is—

The domestic boiler herein described, consisting of the rectangular shell A, the fire-box B at one end thereof, having a water-space at its sides, end, top, and bottom, the smoke-pipe E, free of the boiler-shell, and bent to conform to the shape of the shell and extending through the back thereof, and the pipe L, having the cut-off *d*, in combination with the vessel G', having the pipe *p*, terminating in a nozzle, *n*, by means of which it is coupled to said steam-pipe L, all constructed and arranged to operate as shown and described.

In testimony that I claim the above I have hereunto subscribed my name in the presence of two witnesses.

DAVID FELGAR.
